(57) **CLAIM**

The ornamental design for a self-defense device for a key ring, as shown and described.

DESCRIPTION

FIG. 1 is a top front perspective view of a self-defense device for a key ring, showing my new design; and,

FIG. 2 is a bottom rear perspective view of the self-defense device for a key ring thereof.

The broken line showing of two key rings and four keys in FIGS. 1 and 2 is for illustrative purposes only and forms no part of the claimed design.

1 Claim, 2 Drawing Sheets

FIG. 2
